NATHAN E. VAN STONE AND CHARLES E. DEEDS, OF CHICAGO, ILLINOIS, ASSIGNEES
TO THE SHERWIN-WILLIAMS COMPANY, OF CLEVELAND, OHIO, A CORPORATION OF
OHIO.

FLAKED BETA NAPHTHOL AND PROCESS OF MAKING SAME.

Application filed February 13, 1924. Serial No. 692,480.

This invention relates to a new commercial form of beta naphthol and process for producing the same.

The objects of the invention are to convert molten beta naphthol into thin flakes or chips, having a substantially uniform width and thickness so that they can be used to great advantage for various commercial purposes, being capable of being readily reduced to powder or put into solution in the solvents generally used for this purpose and handled mechanically or by hand safely and expeditiously.

Beta naphthol is initially produced, by the ordinary commercial process, in the form of a white solid and is chemically known as a phenol or naphthol. It is used very generally in a number of commercial processes and is one of the most important materials from which a certain class of dye-stuffs is manufactured. The condition in which it has been heretofore marketed is as a fine powder, or of a fluffy sublimed nature. The usual method heretofore employed for producing these commercial forms of beta naphthol is to run the molten material from the still, into pans, where it is permitted to cool off, then broken into lumps, after which it is reduced to the required fineness in a mill or disintegrator.

Many of the processes using beta naphthol require that it be put into solution in certain weak solvents, other than water, in which beta naphthol is practically insoluble. In order to dissolve beta naphthol in these solvents, in any reasonable or workmanlike time, it is necessary that it be finely divided, and when thus finely divided it has disagreeable and dangerous features, which make it very hard to handle. When freshly ground and in a finely divided state, it is poured or otherwise removed by the user from the package in which it has been shipped by the manufacturer and this results in the material flying out into the air and its irritating properties and obnoxious odor render it exceedingly disagreeable to the workmen who handle it. While its effect on the human organism is not violent, or immediately destructive, it is well known that the cumulative effect of this chemical, as of others in its class, is deterrent to the en-

joyment of normal health and bodily comfort.

Another disadvantage of finely divided beta naphthol is its tendency to cake in the package, when stored, and frequently the contents of the package assume a hard, mass-like structure that is difficult to unpack and which makes it practically impossible to use in the way in which it was intended. It is not commercially feasible to ship in lumps and require the user to grind his own supply, as the grinding of beta naphthol is attended by considerable danger of a dust explosion.

A further objection to the powdered, technical beta naphthol is its tendency to lose its original white or grayish white color, on storage, and become dark brown or otherwise badly discolored. While this discoloration is not an absolute indication of the true quality of the material, it being regarded more as an oxidation of the small amounts of impurities therein than as a change in the beta naphthol itself, it is a bar to the sale of beta naphthol which has been stored for any considerable period of time.

It is the object of this invention to overcome the above-mentioned disadvantages of powdered beta naphthol and provide a new commercial form of the material which does not become caked in the package or lose its original structure, within any reasonable length of time during which it might ordinarily be necessary to store it, say for a period of six months. The invention also has for its object, the production of smooth laminated chips or flakes which present uniform fractures and retain their original color for a relatively long period of time, say for a month to six months.

Our invention will be described in connection with the apparatus illustrated in the accompanying drawings, of which:

Figure 1 is a plan view of a machine for producing beta naphthol in the improved form referred to.

Fig. 2 is a side elevation thereof; and

Fig. 3 is an enlarged detail illustrating the method of flaking the material.

Referring to the drawings, 10 indicates a suitable frame which carries the journal boxes 11 and 12 for the shaft 13. This shaft

has secured thereon a relatively wide faced drum 14 and a pulley 15 by which the drum may be rotated from any suitable source of power. It will be understood that there 5 may be substituted for the pulley 15 any equivalent means for rotating the shaft 13. A pan or receptacle 15' is arranged below the drum 14 and, when the machine is in operation, this receptacle 15' contains molten 10 beta naphthol into which the periphery of the drum 14 dips, the usual level of the molten material being indicated at 15''. It is highly desirable that the receptacle 15' be heated by suitable means for retaining the 15 molten material at the required temperature and, for this purpose, I have shown beneath the receptacle 15' the steam coils 16 but it will be understood that any other suitable heating means may be used. 20 The frame 10 also carries the boxes 17 in which the bearings 18 are adjustable by means of the screws 19. The bearings 18 carry the shaft 20 and this shaft carries a roller 21, the length of which is practically 25 the same as the length of the drum 14. As the drum 14 revolves in the direction of the arrow in Fig. 2, its periphery is coated with the molten beta naphthol, from the receptacle 15', and the roller 21 is adjusted 30 into close relation with the periphery of the drum 14 for the purpose of smoothing out the coarseled beta naphthol to a uniform thickness, which may be regulated by means of the adjusting screws 19. 35 On the opposite side of the drum 14, from the roller 21, the frame 10 carries boxes 22 in which the bearings 23, for the shaft 24, are slidably mounted. The shaft 24 carries a roller 25, the surface of which is fluted or 40 serrated, as best shown in Fig. 3. The bearings 23 are adjustable in the boxes 22 and the edges of the flutes or serrations of the roller 25 are held against the periphery of

the drum 14 by means of springs 26, or other suitable devices, the pressure of which may be regulated by means of screws 27. 45

The rollers 21 and 25 are driven by the drum 14 and by the time the material reaches the roller 25 it has cooled to a practically solid condition and the edges of the flutes 50 or serrations of the roller 25 will indent or cut the material along uniformly spaced parallel lines extending in the direction of the axis of the drum (see Fig. 3).

Below the roller 25 there is a knife or 55 scraper 28 which is adjustable toward and away from the periphery of the drum 14, but which, in the operation of the machine, presses against the periphery of the drum and scrapes the material off as the drum 60 revolves. As will be readily understood, especially from Fig. 3, the material leaves the drum in the form of relatively long strips of uniform width and thickness which, on falling from the knife or scraper 28 into a suitable receiving pan 29, will break up into 65 flakes of varying length.

The flaked beta naphthol thus produced may be safely handled as it will not fly into the air when poured out of a package and, 70 we have found, will not cake in the package, within a reasonable time, or become discolored.

Having thus described our invention, what we claim is:

1. As a new article of manufacture, beta naphthol in the form of flakes of uniform thickness and width. 75
2. As a new article of manufacture, beta naphthol in the form of flakes of uniform thickness. 80

In testimony whereof we affix our signatures.

NATHAN E. VAN STONE.
CHARLES E. DEEDS.
